CLAIM

The ornamental design for a handle portion of a hand stamp, as shown.

DESCRIPTION

FIG. 1 is a front elevational view of a handle portion of a hand stamp showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof; and

FIG. 7 is a perspective view thereof, the broken line showing of a stamp base is environmental only and forms no part of the claimed design.

FIG.3

FIG.1

FIG.2

FIG.5

FIG.4

FIG.6

FIG.7
